No. 15,742.

Patented Jan. 20, 1885.

UNITED STATES PATENT OFFICE.

ALFRED HEALD, OF PHILADELPHIA, PA., ASSIGNOR TO HUGH McCALLUM,
ORLANDO CREASE, AND ANDREW J. SLOAN, ALL OF SAME PLACE.

DESIGN FOR A CARPET.

SPECIFICATION forming part of Design No. 15,742, dated January 20, 1885.

Application filed October 27, 1884. Term of patent 3½ years.

To all whom it may concern:

Be it known that I, ALFRED HEALD, a citizen of the United States, and a resident of Philadelphia, Pennsylvania, have invented or 5 produced a new and original Design for a Carpet-Pattern, of which the following is a specification.

My design is fully shown in the accompanying photograph.

10 The design for the body of the pattern consists of representations of feathers, leaves, and buds of the lotos-plant, and minor ornamental figures of an Egyptian character.

15 The design for the border consists of a central band, *a*, with ornamentation of substantially the same character as that of the body, and inner and outer bands, *b d*, the latter having conventionalized representations of the three-leaved lotos-flower, and minor ornamentation also of an Egyptian character.

I claim—

1. The design for a carpet-pattern, said design consisting of the body portion having representations of feathers, lotos leaves and buds, and minor ornamentation, as shown and de- 25 scribed.

2. The design for a carpet-pattern, said design consisting of the central band, *a*, and inner and outer bands, *b d*, with ornamentation, as shown and described. 30

In testimony whereof I have signed my name to this specification in the presence of two subscribing witnesses.

ALFRED HEALD.
